UNITED STATES PATENT OFFICE.

CHARLES E. JOHNSTON, OF KALAMAZOO, MICHIGAN.

DRAFT DEVICE.

1,183,880.

Specification of Letters Patent. Patented May 23, 1916.

Application filed October 18, 1915. Serial No. 56,534.

To all whom it may concern:

Be it known that I, CHARLES E. JOHNSTON, a citizen of the United States, residing at Kalamazoo, Michigan, have invented certain new and useful Improvements in Draft Devices, of which the following is a specification.

This invention relates to improvements in draft devices.

10 My improved draft device is especially designed by me and I have shown the same in the accompanying drawing as I have embodied it for use in hitching wheeled trailers to automobiles, motor trucks and the like.

15 The main objects of this invention are: First to provide an improved draft device for trailers, which is effective in reducing shocks and strains to the propelling vehicle and trailer. Second, to provide an improved hitching device having these advantages, which is simple and compact in structure and very convenient to use.

20 Further objects, and objects relating to structural details, will definitely appear from the detailed description to follow.

25 I accomplish the objects of my invention by the devices and means described in the following specification.

30 The invention is clearly defined and pointed out in the claims.

35 A structure which is a preferred embodiment of my invention is clearly illustrated in the accompanying drawing, forming a part of this specification, in which:

Figure I is a detail plan view of a structure embodying the features of my invention. Fig. II is a longitudinal vertical section on a line corresponding to line 2—2 of 40 Fig. I. Fig. III is a detail side view with the tongue of the supporting strut in its operative position. Fig. IV is an enlarged detail cross section on a line corresponding to line 4—4 of Fig. I.

45 In the drawing similar reference characters refer to similar parts throughout the several views, and the sectional views are taken looking in the direction of the little arrows at the ends of the section lines.

50 Referring to the drawing, 1 represents the chassis or body of the propelling vehicle and 2 the tongue of the trailer.

55 My improved draft device is especially designed for use on a wheel trailer, the tongue being rigid with the body, but, as such structures are well known and the de-

tails thereof form no part of this invention, I do not illustrate the same herein.

At the forward end of the tongue I secure a pair of side plates 3 by means of the 60 bolts or rivets 4, so that their forward ends project beyond the end of the tongue in a spaced relation to each other to receive the swivel block 5 between them. The swivel block 5 is provided with journals 6 disposed 65 horizontally in suitable bearings 7 provided therefor in the plates 3.

The draw bar 8 is round in cross section and is swiveled in the bearing 9 of the swivel block disposed transversely of its 70 journals 6. At its forward end the draw bar 8 is provided with a head 10 slotted at 11 to receive the coupling member 12, which is secured to the frame 1 by means of suitable bolts 13. The head and coupling members 75 are perforated to receive the coupling bolt 14, which is retained by means of the pin 15.

On the rear end of the draw bar 8 is a 80 castellated nut 16 adjustably retained by means of the pin 17.

A coiled spring 18 is arranged on the draw bar between the head 10 and the swivel block, and a second coiled spring 19 is arranged on the draw bar between the swivel 85 block and the nut 16. These springs act as buffers or shock absorbers, taking the strain and shocks incident to the starting and stopping of the automobile or other vehicle and also the shocks and strains due to uneven roads.

90 The block 5, being free to swivel, provides the horizontal pivotal movement, as is required under varying conditions, and also relieves the parts of shock and strains. The draw bar is free to swivel in the swivel 95 block and is also free to pivot on the coupling bolt 14, thus making a connection which is very flexible and at the same time strong and durable.

To support the tongue when unhitched from the propelling vehicle I provide a strut 20 which is pivoted at the side of the plates 3 by the bolt 21. The plates are provided with lugs 22 for supporting the strut in an inclined position, see Figs. I and III. The 105 strut may be swung rearwardly against the under side of the tongue and retained by a suitable catch or hook, not illustrated.

110 The connection is a complete universal joint so that in turning the vehicle shortly the joint will allow the trailer to follow without cramping the pole. The joint also

allows, as stated, for inequalities of the road, allowing the trailer to follow over ruts and hummocks without straining the drawing vehicle.

5 Having thus described my invention, what I claim as new and desire to secure by Letters Patent, is:

1. In a draft device, the combination with a tongue, of a pair of plates secured to the 10 sides of said tongue to project forwardly therefrom in a spaced relation, a swivel block journaled between said plates, the journals of said block being horizontally disposed, a draw bar swiveled in said journal block and having a horizontally slotted head, a nut threaded upon the rear end 15 of said draw bar for adjustment thereon, coiled springs arranged on said draw bar between said head and said swivel block and 20 between said nut and said swivel block, a

coupling member disposed in said slotted head, and a coupling bolt disposed vertically through said head and coupling member.

2. In a draft device, the combination with 25 a pair of spaced plates, a swivel block journaled between said plates, a draw bar swiveled in said journal block and having a head adapted as a coupling member, coiled springs arranged on said draw bar between said 30 head and said swivel block and at the rear of said block, and a support on said draw bar for the rear end of the rear spring.

In witness whereof, I have hereunto set my hand and seal in the presence of two 35 witnesses.

CHARLES E. JOHNSTON. [L.S.]
Witnesses:

LUELLA G. GREENFIELD,
GRACE B. THOMPSON.
